UNITED STATES PATENT OFFICE.

FREDERICK R. SEIDENSTICKER, OF WEST MERIDEN, CONN., ASSIGNOR TO
BRADLEY & HUBBARD, OF SAME PLACE.

DESIGN FOR LAMP-BRACKET.

Specification forming part of Design No. **8,041**, dated February 2, 1875; application filed June 3, 1874.
[Term of Patent 7 years.]

CASE C.

To all whom it may concern:

Be it known that I, FREDERICK R. SEIDENSTICKER, of West Meriden, in the county of New Haven and State of Connecticut, have invented a new Design for Lamp-Bracket; and I do hereby declare the following, when taken in connection with the accompanying illustration, to be a full, clear, and exact description of the same, and which said illustration constitutes part of this specification, and represents a perspective view.

This invention relates to a design for bracket for supporting a lamp or other burner; and consists in the peculiar configuration of the base and arm together or separately, as more fully hereinafter described.

The base is of substantially quadrangular form, its angles slightly cut, with lines running from the angles to a central boss, A, where the arm is attached. An ear, B, at the top and bottom serves to ornament the base, and as a means for securing the base. The bracket-arm at the base shows two connected cubes, *a a*, the first connecting with the base.

From the other the arm rises perpendicularly, then turns, *b*, at right angles for a short distance, thence down in a curve, *d*, its end turning up in the continued curve, and terminating in a pair of scrolls, *e f*, upon which the lamp rests, the inner scroll continued back onto the arm. A fan-shaped ornament, *g*, upon the under side of the arm, runs up toward the base in form of a brace.

I claim as my invention—

1. The design for base for lamp-bracket, consisting of the quadrangular form, the angles cut and lines running toward the center, as shown and described.

2. The design for lamp-bracket, consisting of the connected cubes *a a*, from the outer one of which the arm rises and turns at right angles, thence curved downward, and terminating in a pair of scrolls, *e f*, and fan-shaped ornament *g*, as shown and described.

FREDERICK R. SEIDENSTICKER.
